UNITED STATES PATENT OFFICE.

SOPHIA A. CARLSON, OF CHISHOLM, MINNESOTA.

GARMENT.

1,281,290.

Specification of Letters Patent. Patented Oct. 15, 1918.

Application filed May 2, 1917. Serial No. 165,986.

To all whom it may concern:

Be it known that I, SOPHIA A. CARLSON, a citizen of the United States, residing at Chisholm, in the county of Saint Louis and 5 State of Minnesota, have invented certain new and useful Improvements in Garments, of which the following is a specification.

This invention relates to improvements in garments for women, and more particularly to those of the knit combination shirt 10 and drawers type.

The object of the invention is to provide a garment of this character equipped with an improved attachment for supporting 15 catamenial bandages so constructed and arranged as to be completely concealed when not in use and so positioned as to be out of contact with the person of the wearer, and which may yet be readily arranged for 20 use when desired.

Another object is to provide a garment of this character equipped with this improved attachment and having improved reinforcing means for withstanding the 25 strains exerted on the garment by such bandages when in use.

With the foregoing and other objects in view, which will appear as the description proceeds, the invention resides in the combination and arrangement of parts and in the details of construction hereinafter described and claimed, it being understood that changes in the precise embodiment of the invention herein disclosed may be 35 made within the scope of what is claimed without departing from the spirit of the invention.

In the accompanying drawings:—

Figure 1 represents a front elevation of a 40 knit union garment equipped with this invention,

Fig. 2 is a rear elevation of a portion thereof,

Fig. 3 is a longitudinal vertical section 45 thereof,

Fig. 4 is a detail perspective view of one of the bandage supporting tabs.

In the form illustrated, a combination garment 1 is shown embodying the usual 50 shirt 2 and drawers 3. It is well known that with a garment of this character, the use of a separate sanitary belt for supporting catamenial bandages is undesirable for the reason that when worn outside the garment, the bandage is ineffective to protect 55 said garment and when worn underneath the garment, it is inaccessible for change of

the bandage when the wearer is dressed; and should no belt at all be worn and the bandage simply pinned to the garment, the latter is torn by such pinning and often-times soiled in addition. It is to overcome these disadvantages in garments of this character that this invention is designed.

Union garments of this character, which are usually made of knit goods, are provided at the front and rear thereof with overlapping flaps 4 and 5, flap 5 being here shown arranged outside and overlapping flap 4. This arrangement of flaps is substantially 70 duplicated at the rear of the garment and shown at 4' and 5', except that their upper ends are located higher up, nearer the waistline of the garment for obvious reasons.

Arranged between flaps 4 and 5 is a tab 6 preferably constructed of an elastic strip 7 and a non-elastic pinning member 8 preferably composed of canton flannel or any other suitable washable fabric. This tab 80 6 is disposed between the garment flaps at the front of the garment and the free end of the elastic strip 7 is secured to the garment adjacent the meeting or inner ends of the flaps 4 and 5 as is shown clearly in Figs. 85 1 and 2. When not in use, this tab 6 is completely concealed between the flaps as is shown in dotted lines in Fig. 1. The inner flap 4 has an opening 9, here shown arranged transversely across the flap and preferably reinforced by buttonhole stitching or otherwise to resist strains and through which the tab 6 is designed to pass when it is to be used for supporting a bandage (not shown), it being understood that the bandage 95 is pinned at its opposite ends to the pinning member 8 carried by tab 6 and to another pinning member 8' of tab 6' at the rear of the garment (see Fig. 2). The tab 6' which is exactly like tab 6 is disposed between flaps 4' and 5' and is secured to flap 4' at a point below the connected ends of said flaps, and is adapted to extend through an opening 9' in flap 4' when desired for use. A reinforcing strip 10 is stitched to 100 flap 4' as shown in Fig. 2 and is designed to resist the strains borne by tab 6' to prevent tearing of the garment.

The garment is also reinforced by a strip 11 of inelastic material, which is arranged 110 as shown in Fig. 1 to resist the strain exerted on the garment by the bandage when in use, the bandage not being herein shown as it forms no part of this invention.

This strip is preferably arranged to simulate a belt, the upper and lower edges of which are formed by the strip, and which also has an additional member 12 simulating 5 a tab formed by the strip.

The rear flaps are preferably secured in overlapping relation by means of a button and buttonhole indicated at 13, although any other suitable fasteners may be employed.

- 10 A reinforcing strip 14 of non-elastic material is secured around the edges of each front flap and an overlapping flap 5' at the rear and operates as a support for the bandage, which when in use rests on the lapped flaps.
- 15 This strip also prevents undue stretching and curling of these edges when no bandage is needed. It is obvious that if these strips were not used, the elastic nature of the fabric would permit the flaps to open under the 20 weight of the bandage and allow it to project between them and thus cause soiling of the flaps.

It will thus be seen that a garment constructed as herein described will meet all the 25 requirements above set forth and when it is not necessary to use a bandage, the tabs 6 and 6' may be drawn through the openings 9 and 9' formed in the inner flaps 4 and 4' of the garment and positioned between said 30 flaps so that they will not contact with the body of the wearer to prevent chafing of the body and soiling of the tabs and they will also be out of sight.

When it is desired to use the tabs they are 35 inserted through the reinforced openings 9 and 9' with their pinning ends depending inside the garment ready for engagement with the bandage, and which are thus accessible when it is desired to change the bandage 40 after the corset has been put on and the wearer fully dressed.

From the foregoing description, taken in connection with the accompanying drawings, the advantages of the construction and of 45 the method of operation will be readily apparent to those skilled in the art to which the invention appertains and while I have described the principle of operation of the invention together with the device which I 50 now consider to be the best embodiment thereof, I desire to have it understood that the device shown is merely illustrative and that such changes may be made as are within the scope of the claimed invention.

55 I claim:—

1. A nether garment for women having an open crotch with overlapping flaps at its front and rear, and bandage attaching means arranged between said flaps, the inner flap 60 having an opening for the passage therethrough of said means when the latter are desired for use.

2. A nether garment for women having an

open crotch with overlapping flaps at its front and rear, bandage attaching tabs secured between said flaps, each of said inner flaps having an opening therein for the passage of a tab so as to position the latter adjacent the body of the wearer ready for use. 65

3. A nether garment for women having an open crotch with overlapping flaps at its front and rear, bandage attaching tabs composed of elastic strips secured at one end between said flaps adjacent their point of connection and provided at its free end with a 70 non-elastic pinning member, each of said inner flaps having an opening extending transversely thereof for the passage therethrough of the tab when desired for use and permitting it to be withdrawn and disposed between the flaps when not in use. 75

4. A nether garment for women composed of knit material and having a reinforcing strip arranged around the waist thereof to simulate a downwardly curved belt, said 80 garment having an open crotch with overlapping flaps at its front and rear, said reinforcing belt forming strip extending adjacent the inner ends of said flaps, bandage attaching tabs secured at one end to the garment between the flaps adjacent the belt forming strip whereby any strains exerted on the tabs will be borne by the strip, the inner flaps at the front and rear of the garment having transversely extending reinforced openings for the passage of the tabs 85 therethrough. 90

5. A garment of the class described including a pair of knit fabric open drawers having overlapping flaps at the crotch with 100 reinforcing strips of non-stretchable material along the edges of said flaps, the inner flaps having openings therein and bandage attaching tabs carried by said garment between said flaps and adapted to extend 105 through said openings when desired for use, whereby the weight of the bandage will be supported by said strips.

6. A knit bifurcated nether garment for women having an open crotch with overlapping flaps at its front and rear, a strip of inelastic material secured around the waist portion of said garment and arranged to simulate a belt with a tab at the front thereof, tabs arranged between said flaps and positioned so that the strain exerted thereon 115 will be borne by said strip, the inner flap having openings through which said tabs may be passed when desired for use.

In testimony whereof I affix my signature 120 in presence of two witnesses.

SOPHIA A. CARLSON.
